UNITED STATES PATENT OFFICE.

GARRETT F. SPEER, OF PHILADELPHIA, PENNSYLVANIA.

PAPER-DRYING MACHINE.

SPECIFICATION forming part of Letters Patent No. 235,586, dated December 14, 1880.

Application filed November 16, 1880. (No model.)

To all whom it may concern:

Be it known that I, GARRETT F. SPEER, of the city and county of Philadelphia, and State of Pennsylvania, have invented certain new and useful Improvements in Paper-Drying Machines; and I do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 is a longitudinal section of my improved drying apparatus. Fig. 2 is a front-end view of the same. Fig. 3 is a perspective view of the mouth of the air-tube.

The same letter indicates the same part wherever it occurs in the drawings.

My invention relates to the drying of paper to one side of which size has been applied; and it consists in the peculiar construction of an apparatus by which the sized paper from a continuous roll is made to pass through a long closed chamber, and to receive during its passage the impact of a strong current of cold air, so directed as to strike the surface of the paper at an acute angle with its surface, said current producing, by its movement, a tendency to a vacuum beneath the moving sheet, and thus holding it closely upon its supporting-rollers, all substantially in the manner hereinafter more specifically set forth.

In the accompanying drawings, which fully illustrate my invention, F marks a rotary fan of ordinary construction, operated by a belt from a pulley driven by any suitable power. From this fan an air-tube, T, extends downward and enters the front end of a long closed box, B, the mouth of the tube being enlarged and flattened, as shown in Fig. 3, so that it will fit into a long slot, S, cut in the end of the box B to receive it.

The area of the mouth of the tube is equal to the area of its body, so that the air is under equal pressure throughout, and the area of the outlet of the box B is the same as that of the slot S, for the same purpose.

The paper to be sized and dried is in a continuous roll, hung in the frame A at R, its movement being controlled by a weighted brake, W, in the ordinary way. It passes from the roll R, over rollers r' r^2 , thence through a slot, V, in the bottom of the front end of the

box B and over a series of rollers, $r r$, placed diagonally in the box, as shown, then out at a slot in the top of the rear end of box B, over calender-rolls D E, and is finally wound, in a dry and finished state, on the roller R'.

As the sheet passes over roller r' , a paste-roll, a, turning in a size-box, C, applies size to its surface in the usual way.

It will be observed that the current of air is, in great measure, confined to the upper portion of the box, and, by a well-known law of fluid motion, it tends, by its rapid course, to draw the air out of the lower part of the box, and thus produce such a tendency to a vacuum there as will cause the paper to press tightly upon the top of the rollers r over which it is passing, and thus prevent the fluttering and tearing of the paper.

The cover of box B is made removable, in sections, to allow of the inspection of any part of the paper at pleasure.

The calenders D E may be used cold or hot, as preferred; but I have obtained the best results without the use of heat, the paper so produced being superior in strength and quality to that passed over steam-heated calenders, the tendency of the heat being to make the size brittle and impair the purity of its color.

I have found the use of cold air perfectly efficient in the rapid drying of the paper, as I am able, in an apparatus of this character, to dry from twenty to thirty feet a minute in a superior manner.

What I claim as my invention, and desire to secure by Letters Patent, is—

The paper-drying apparatus hereinbefore described, the same consisting of the combination of the cold-air fan F, tube T, with its enlarged mouth M, the closed box B, provided with the slots S V, the rollers $r r$, diagonally placed, as shown, and the air-outlet O, and mechanism for drawing the paper through the apparatus and winding it in a roll when finished, the whole constructed, arranged, and operating substantially in the manner specified.

In testimony that I claim the foregoing as my own invention I affix my signature in presence of two witnesses.

GARRETT F. SPEER.

Witnesses:

L. C. YOUNG,
CHAS. F. STANSBURY.
